UNITED STATES PATENT OFFICE.

WADE H. WINEMAN, OF CHICAGO, ILLINOIS, ASSIGNOR TO SULLIVAN MACHINERY COMPANY, A CORPORATION OF MASSACHUSETTS.

FORGING MACHINE.

Application filed December 31, 1917. Serial No. 209,793.

To all whom it may concern:

Be it known that I, WADE H. WINEMAN, a citizen of the United States, residing at Chicago, in the county of Cook and State 5 of Illinois, have invented certain new and useful Improvements in Forging Machines, of which the following is a full, clear and exact specification.

My invention relates to forging machines. 10 It has heretofore been proposed to attach the anvil of a forging machine to its supporting frame by means of shims or the like, and, in certain instances, to provide between the anvil of a forging machine and 15 the frame thereof, an intermediate base block which is in turn attached to the frame by means of shims. These constructions have, however, decided objections arising from the fact that the wear between the 20 parts constantly tends to loosen the shims. Moreover, these objections are especially apparent when shims are used in connection with forging machines of the drill sharpener type, as in such machines it is desirable to 25 utilize a large and expensive casting for the main frame of the machine, and repeated driving and re-driving of the shims as wear takes place often results in such mutilation 30 of the casting as to require the same to be replaced.

My invention has for its object to provide an improved means whereby the anvil of a forging machine may be attached to its supporting frame and held in rigid relation 35 thereto despite wear between the parts. A further object of my invention is to provide an improved wear absorbing means for fastening the base block of a forging machine to the frame thereof in such a manner 40 that all necessity for scarring or otherwise mutilating the frame by the driving of shims or the like between the base block and the frame is entirely overcome, my improved mechanism acting automatically to 45 take up wear as it occurs. These and other objects and advantages of my improved construction will, however, hereinafter more fully appear.

In the accompanying drawings, I have 50 shown for purposes of illustration one embodiment which my invention may assume in

practice, illustrating the same as applied to use in connection with a standard form of drill forming and sharpening machine.

In these drawings,

Fig. 1 is an end elevation of such a machine equipped with my improvement.

Fig. 2 is a detail view taken substantially on line 2—2 of Fig. 1.

Fig. 3 is a detail view taken substantially on line 3—3 of Fig. 2.

In this illustrative construction, it will be noted that I have shown a forging machine of the well known Sullivan type including a cast base frame 1 having a standard 2 thereon on which is carried a percussive motor 3 adapted to reciprocate an upper swaging die 4 into and out of engagement with a lower stationary swaging die or anvil 5 supported on the frame 1, the operation of the motor being controlled through a suitable controlling mechanism 6, which is in turn controlled by a foot lever 7. As usual in this type of machine, suitable cooperating upsetting mechanism is provided which is adapted to be controlled by a controlling lever 8, but as this mechanism does not enter into the present invention a detail description of the same is believed to be unnecessary.

In my improved construction it will be noted that the lower swaging die 5 rests upon a base block 9, and that this die 5 is provided with a depending dove-tailed portion 10 on its lower surface adapted to be received in a corresponding aperture in the upper surface of the base block and to be held rigidly in position in that aperture by suitable means, herein shown in the form of a shim 11. As illustrated, this base block 9 is disposed in a suitable aperture or seat 12 formed in the frame 1. The base block 9, as shown herein, is also provided at each of its opposite ends with communicating slots 13 and holes 14 adapted respectively to receive the heads and shanks of a plurality of vertically disposed bolts 15 which extend down through these apertures and corresponding apertures 16 in the frame 1, into a large lower aperture 17 in the latter, in turn accessible through an opening 18 in the front of the frame. Here, it will

be noted that each of these bolts carries on its lower end a coiled spring 19 disposed between a plurality of washers 20 thereon, one of which is pressed against the upper 5 surface of the aperture 17, while the other engages an adjustable nut 21 accessible through the aperture 18.

In this improved construction, it will be noted that the members 5 and 9, taken together, may be considered to constitute an anvil, and it will be observed that no matter what wear may take place between the base block 9 and the frame 1, this wear as it occurs will be automatically taken up by the 10 springs 19, which constantly tend to force the base block against the bottom surface of the aperture 12 on the frame. It will also be noted that due to the location of the two bolts 15 at opposite sides of the center line 15 of the block 9, the latter is acted upon by the springs 19 in such a manner as to hold it very securely in position. As a result of my improved construction, it will be observed that all necessity for driving any 20 shims or wedges between the block 9 and the frame 1 is entirely eliminated. It will also be noted that the lower die 5 may be readily attached to the base block by any desired means, such as the shim 11, without any danger of mutilation, since the base block may 25 be, and preferably is, formed of steel, and is therefore less susceptible to damage than the cast frame. Obviously here also, should the block be damaged, the same can be readily 30 replaced at a very small fraction of the cost involved in providing a new frame. Attention is here also directed to the fact that when it is desired to adjust the tension of the springs 19, the same are readily accessible 35 for adjustment through the aperture 18 in the front of the frame. These and other advantages of my improved and simplified construction will, however, be clearly apparent to those skilled in the art.

40 While I have in this application specifically described one embodiment which my invention may assume in practice, it will be understood that this form of the same is used for purposes of illustration, and that 45 the invention may be modified and embodied in other forms without departing from its spirit or the scope of the appended claims.

50 What I claim as new and desire to secure by Letters Patent is:

- 55 1. In a forging machine, a frame, an anvil thereon, and means operative automatically to constantly maintain the anvil in rigid relation to the frame despite wear therebetween.
- 60 2. In a forging machine, a frame, an anvil thereon, and means for automatically taking up wear between said members comprising elastic means for maintaining said members in rigid relation.
- 65 3. In a forging machine, a frame, an an-

vil thereon, and automatically acting spring pressed means for taking up the wear between the same.

4. In a forging machine, a frame, an anvil thereon, and resilient tensioning means for holding said anvil in position on said frame. 70

5. In a forging machine, a frame, an anvil thereon, means operative when under tension to retain said anvil rigidly seated on said frame, and means cooperating with said last 75 mentioned means for maintaining it under tension despite wear between said anvil and frame.

6. In a forging machine, a frame, an anvil thereon, means operative when under tension 80 to hold said anvil in rigid relation to said frame, means for placing said holding means under tension, and means for changing the tension of said last mentioned means. 85

7. In a forging machine, a frame, an anvil thereon, means operative when under tension for holding said anvil in rigid relation to said frame, means for placing said holding means under tension, and means for increasing the tension of said last mentioned 90 means when it is reduced by wear of the parts.

8. In a forging machine, a frame, an anvil thereon, and means including a plurality 95 of spring pressed members for taking up the wear between the same.

9. In a forging machine, a frame, an anvil thereon, a clamping member, and resilient means for holding said member in clamping position irrespective of wear of the parts. 100

10. In a forging machine, a frame, an anvil thereon, and automatically acting means constituting the sole attaching means for said elements and operative to maintain the anvil constantly in rigid relation to the 105 frame despite wear between the parts.

11. In a forging machine, a frame, having an aperture therein, a base block carried on said frame, and spring pressed clamping means therefor extending into said aperture. 110

12. In a forging machine, a frame having an aperture accessible from the exterior thereof, a base block carried on said frame, and spring pressed clamping means therefor extending into said aperture. 115

13. In a forging machine, a frame, a base block thereon adapted to receive an anvil block, and spring pressed means for attaching said base block to said frame and absorbing the wear between the parts. 120

14. In a forging machine, a frame, a base block thereon, an anvil block fixed to said base block, and automatically acting means for attaching said base block to said frame and maintaining the base block constantly in rigid relation to the frame despite wear therebetween. 125

15. In a forging machine, a frame having an aperture therein, a base block on said frame, an anvil block carried by said base 130

block, clamping members extending through said base block into said aperture, and resilient means disposed in said aperture for taking up the wear between said base block and said frame.

16. In a forging machine, a frame having an aperture accessible from the exterior thereof, a base block on said frame, an anvil block on said base block, clamping members extending through said base block and frame into said aperture, and resilient wear absorbing means acting upon said clamping members and disposed in said aperture.

17. In a forging machine, a frame having an aperture therein, a seat on the frame, a base block on said seat, an anvil block carried by said base block, clamping members extending through said base block into said aperture, and resilient means disposed in said aperture for taking up the wear between said base block and seat.

18. In a forging machine, a frame having an aperture therein, a recessed seat on the frame, a base block on said seat, said recessed seat being adapted to receive and position said base block, an anvil block carried by said base block, and clamping members ex-

tending through said base block into said aperture for taking up the wear between said base block and seat.

19. A die carrying means for forging machines including a frame provided with an opening therein, a swaging member, a base block therefor seated on said frame, a bolt carried by said base block and extending vertically in the direction of impact into said opening, and spring means acting between said bolt and frame for absorbing the wear between said base block and frame and holding said block in seated position.

20. A die carrying means for forging machines including a frame having an aperture accessible from the exterior thereof, said frame presenting a groove, a swaging member, a base block therefor seated in said groove, bolts carried by said base block and extending downwardly through said frame into said aperture, and spring means acting on said bolts for absorbing wear between said base block and frame and holding said base block in seated position.

In testimony whereof I affix my signature.

WADE H. WINEMAN.
